ABSTRACT: A ternary logic circuit, in which values of series-connected two controllable resistances to which plus potential and minus potential are respectively applied are controlled by a common input voltage. The output of the ternary logic circuit assuming one of three possible values in accordance with the value of the input voltage is obtained across a nonlinear load resistance connected across the ground and a junction between the two controllable resistances.

TERNARY LOGIC CIRCUIT

This invention relates to ternary logic circuits.

A ternary logic system using ternary logic circuits has such advantage that the number of necessary logic circuits can be reduced in comparison with a binary logic system using binary logic circuits in designing a logic system, such as a computer. However, since ternary logic circuits suitable to readily reduce to practice have not yet been proposed, this ternary logic system has not yet been reduced to practice.

An object of this invention is to provide ternary logic circuits of simple construction suitable to be readily reduced to practice.

The principle, construction and operation of the ternary logic circuit of this invention will be better understood from the following detailed discussion in conjunction with the accompanying drawings, in which:

FIG. 1 is a block diagram for describing the principle of this invention;

FIG. 2 shows characteristic curves explanatory of the characteristics of controllable resistances used in the circuit shown in FIG. 1;

FIG. 3 shows a characteristic curve explanatory of the characteristic of a nonlinear load resistance used in the circuit shown in FIG. 1;

FIG. 4 shows input-output characteristics of the circuit shown in FIG. 1; and

FIG. 5 is a circuit diagram for illustrating an embodiment of this invention.

With reference to FIG. 1, a ternary logic circuit of this invention comprises a first controllable resistance R_1 , a second controllable resistance R_2 connected in series to the first controllable resistance R_1 , a DC source $+E_1$ applying a plus DC voltage to the first controllable resistance R_1 , a DC source $-E_2$ applying a minus DC voltage to the second controllable resistance R_2 , and a load resistance RL connected across the ground E and a junction J_o between the first controllable resistance R_1 and the second controllable resistance R_2 . An input voltage V_i supplied across terminals 1 and $1a$ is commonly applied to respective input terminals I_1 and I_2 of the first and second controllable resistances R_1 and R_2 . In this case, the value of one of the first and second controllable resistances R_1 and R_2 increases continuously as the value of the input voltage V_i increases as shown by a curve a in FIG. 2. On the other hand, the value of the other of the first and second controllable resistances R_1 and R_2 decreases continuously as shown by a curve b in FIG. 2. Moreover, the load resistance RL has a double N-shaped nonlinear voltage-current characteristic as shown in FIG. 3 in which the load resistance RL has a N-shaped voltage-current characteristic in each of plus and minus current regions. In other words, the terminal voltage V_o of the load resistance RL assumes a low value until the current I of the load resistance RL exceeds a plus threshold level I_{p1} or a minus threshold level I_{m1} after starting from zero and assumes one of two possible values when the current I of the load resistance RL exceeds the plus and minus threshold levels I_{p1} and I_{m1} . The two possible values are substantially constant plus and minus values each higher than the low value. In this case, the plus constant value is obtained when the current I exceeds the plus threshold level I_{p2} , and the minus constant value is obtained when the current I exceeds the minus threshold level I_{m2} .

To obtain a preferred input-output characteristic described below, it is desirable that each of two peak voltages V_{p1} and V_{p2} in a voltage-current curve c is small as far as possible. Moreover, it is desirable that the slope of the curve c is sharp as far as possible when the terminal voltage V_o of the load resistance RL exceeds either a minimum voltage V_{m2} or V_{p1} . In the following description, it is assumed that these conditions are satisfied for simple description.

In operation, the voltages of the DC sources $+E_1$ and $-E_2$ are so adjusted that the current I flowing through the load re-

sistance RL is zero when the input voltage V_i is zero. Accordingly, the potential of the junction J_o is also zero in this case. In this condition, the input voltage V_i of positive pulse is applied across terminals 1 and $1a$ as shown in FIG. 2. In accordance with this application of the input voltage V_i , the value of the first controllable resistance R_1 increases along the curve a and reaches a value r_1 while the value of the second controllable resistance R_2 decreases along the curve b and reaches a value r_2 . Accordingly, since the potential of the junction J_o is shifted to a minus value from zero, the current I flows from the ground E to the junction J_o . In this case, the output voltage V_o generated across the load resistance RL is determined in accordance with the characteristic shown in FIG. 3. When the input voltage V_i increases to the plus side from zero, the current I increases to the minus side. Since the operating point of the load resistance RL exists between points O and p_1 on the curve c until the current I exceeds a value I_{p1} , the output voltage V_o increases gradually up to a value V_{p1} . However, the value of the output voltage V_o is very low in this condition. When the current I exceeds the value I_{p1} in accordance with increase of the input voltage V_i , the operating point of the load resistance RL jumps over a negative resistance region (from the point P_1 to a point V_1) to a point B along a load line m of the load resistance RL . In this case, the slope of the load line m can be approximately deemed as the value of the load resistance RL . Accordingly, the value of the output voltage V_o increases suddenly from the value V_{p1} to a value $-V_B$. In a case where the input voltage V_i further increases to the minus side, since the curve c has a sharp slope at the outside of the point B , the output voltage V_o is substantially constant while the increase of the output voltage V_o is negligible.

The above-mentioned operation is a section O-M of an input-output characteristic shown in FIG. 4 in which the abscissa is the value of the input voltage V_i and the ordinate is the value of the output voltage V_o . In this case, a value V_{T1} is the value of the input voltage V_i when the current I is equal to the value I_{p1} . As understood from this characteristic, (1) the output voltage V_o assumes a very low value substantially equal to zero if the input voltage V_i falls in a first region from zero to the voltage V_{T1} ; (2) the output voltage V_o jumps to the value $-V_B$ at a condition where the input voltage V_i is equal to the voltage V_{T1} ; and (3) the output voltage V_o is substantially zero while it increases by insensible transitions if the input voltage V_i increases in a second region exceeding the voltage V_{T1} . On the other hand, if the input voltage V_i decreases from the second region ($V_i > V_{T1}$) to zero along the curve c , the jump over the negative resistance region is started at the point V_1 shown in FIG. 3. This jumping is started in FIG. 4 at a value slightly shifted to zero from the value V_{T1} . This hysteresis characteristic is substantially negligible in comparison with the value V_{T1} if the resistances of the controllable resistances R_1 and R_2 are small as far as possible under nonoscillation of this circuit. Accordingly, a curve d shown in FIG. 4 can be substantially deemed as a single curve.

The above operations relate to a case where the input voltage V_i is plus. However, if references P_1 , V_1 , I_{p1} , B and $-V_B$ etc. shown in FIG. 3 are respectively replaced by references P_2 , V_2 , I_{p2} , A and V_A etc. in the same FIG. 3, a section O-N of the input-output characteristic corresponding to a case where the input voltage V_i has a minus polarity can be obtained as shown in FIG. 4. In this case, the value V_{T2} is the value of the input voltage V_i in a case where the current I is equal to the value I_{p2} , and a value V_A shown in FIGS. 3 and 4 can be deemed as the value of the output voltage V_o in a region where the input voltage V_i exceeds the value V_{T2} .

Accordingly, the value of the output voltage V_o of the circuit assumes (1) substantially zero in a case where $V_{T2} < V_i < V_{T1}$; (2) substantially the value $-V_B$ in a case where $V_i > V_{T1}$; and (3) substantially the value V_A in a case $V_i < V_{T2}$. The values V_{T1} , V_{T2} , $-V_B$ and V_A characterizing the characteristic of this circuit shown in FIG. 1 are determined by the threshold currents I_{p1} and I_{p2} and the minimum voltages V_{m1} and V_{m2} .

As described below, the nonlinear load resistance means RL can be realized by the use of a series-connection of Esaki-diodes (tunnel diodes) so as to have the characteristic shown in FIG. 3. In this case, the values I_{p1} and I_{p2} can be determined as desired; and values V_{T1} and V_{T2} can be varied by changing the material of the Esaki diodes or can be varied in a terraced manner by changing the number of series-connected Esaki diodes. As understood from above, the characteristic values V_{T1} , V_{T2} , $-V_B$ and V_A can be varied in respective wide ranges. In this case, since the jumping speed at the values V_{T1} and V_{T2} are very high, the circuit of this invention performs a high speed ternary pulse-reshaping operation.

Moreover, ratios V_A/V_{T1} and $-V_B/V_{T2}$ which are deemed as the amplification constant of this circuit are determined by the sensitivity of the controllable resistances R_1 and R_2 (i.e.; the slope R/V of the curves a and b shown in FIG. 2). In other words, the amplification constant of this circuit becomes higher as the slope of the curves a and b becomes sharper. In an embodiment described below, transistors are used as the controllable resistances R_1 and R_2 . In this case, the amplification constant of this circuit becomes higher as the current amplification factor h_{FE} becomes larger.

In the above description, it is assumed that the respective characteristics of the first controllable resistance R_1 and the second controllable resistance R_2 are shown respectively as the curves a and b in FIG. 2. However, the respective characteristics of the resistances R_1 and R_2 may be respectively the curves b and a . In this case, the input-output characteristic of this circuit is shown as a dotted curve e shown in FIG. 4, in which the polarity of the output voltage V_o is inverted against the curve d .

The circuit of this invention is a ternary pulse reshaping-amplifying circuit having the above mentioned function. Moreover, this circuit of this invention can be applied to perform ternary logical NOT f_n , ternary logical OR f_{or} , ternary logical AND f_{and} , ternary logical NOR f_{nor} and ternary logical NAND f_{nand} proposed by Post-Lukasiewicz. Conditions in this case will be described below.

Now, it is assumed that ternary digits are "1," " Φ " and "0" and the relationship " 1 ">" Φ ">"0" is to be decided. In this case, if it is assumed that N logical variables each assuming one of three possible values "1," " Φ " and "0" are respectively designated by notations x_1 , x_2 , ..., x_N , the above-mentioned ternary logical NOT f_n , ternary logical OR f_{or} , ternary logical AND f_{and} , ternary logical NOR f_{nor} and ternary logical NAND f_{nand} are defined respectively as follows:

$$\begin{aligned} f_n: f_n(1) &= 0; f_n(\Phi) = \Phi; f_n(0) = 1 \\ f_{or}: f_{or}(x_1, x_2, \dots, x_N) &= \max(x_1, \dots, x_N) \\ f_{and}: f_{and}(x_1, x_2, \dots, x_N) &= \min(x_1, x_2, \dots, x_N) \\ f_{nor}: f_{nor}(x_1, x_2, \dots, x_N) &= f_n(f_{or}(x_1, \dots, x_N)) \\ f_{nand}: f(x_1, x_2, \dots, x_N) &= f_n(f_{and}(x_1, x_2, \dots, x_N)) \end{aligned}$$

In the circuit shown in FIG. 1, the ternary logical digits "1," " Φ " and "0" correspond respectively to the values V_A , 0 , $-V_B$. In this condition, the input voltage V_i is one of the above mentioned logical variables x_1 , x_2 , ..., x_N .

In this case, if it is assumed that the value V_A is more than the value V_{T1} and the value $-V_B$ is less than the value V_{T2} in the characteristic shown in FIG. 4, the ternary logical NOT f_n corresponds to the curve d . In the case of the curve e , the circuit of this invention can be used as a simple reshaping-amplifying circuit for a ternary pulse signal in accordance with an equivalent function.

If it is assumed that the sum of N different variables corresponds to the input voltage V_i , the curve d corresponds to the ternary logical NOR f_{nor} and the curve e corresponds to the ternary logical OR f_{or} in a case where (1) the value V_A is more than a value $(N-1)V_B$, (2) a value $(V_A - (N-1)V_B)$ is more than the value V_{T1} , and (3) the value V_{T2} is less than a value $-(N-1)V_B$ and more than a value $-NV_B$. On the other hand, in a case where (1) the value V_B is more than a value $(N-1)V_A$, (2) the value V_{T1} is less than a value NV_A and less than a value $(N-1)V_A$, and (3) the value V_{T2} is less than a value $((N-1)V_A - V_B)$, the curves d and e correspond respec-

tively to the ternary logical NAND f_{nand} and the ternary logical AND f_{and} .

With reference to FIG. 5, an embodiment of this invention comprises a PNP transistor TR_1 used as the first controllable resistance, a NPN transistor TR_2 used as the second controllable resistance, and a series-connection of two sets of Esaki diodes ED_1 and ED_2 which are oppositely series-connected to each other and used as the load resistance RL . In this case, each of the sets of Esaki diodes ED_1 and ED_2 comprises a plurality of Esaki diodes which are series-connected to one another in the same direction. The respective emitter-collector paths of the transistors TR_1 and TR_2 are series-connected to each other. The series-connection of the two sets of Esaki diodes ED_1 and ED_2 is connected across the ground E and a junction J_o between collectors of the transistors TR_1 and TR_2 . A DC source $+E_1$ applies a plus voltage to the emitter of the transistor TR_1 , and a DC source $-E_2$ applies a minus voltage to the emitter of the transistor TR_2 . An input voltage V_i is applied through respective resistors R_{B1} and R_{B2} to bases of the transistors TR_1 and TR_2 respectively. The output voltage V_o is obtained across the series-connection of Esaki diodes ED_1 and ED_2 .

In this embodiment, the respective resistances of the emitter-collector paths of the transistors TR_1 and TR_2 are controlled by the input voltage V_i and varied as shown by the curves a and b in FIG. 2. The voltage-current characteristic of the load resistance comprising the series-connection of the two sets of Esaki diodes ED_1 and ED_2 varies along the curve c shown in FIG. 3. In this case, a right half of the curve c divided by the ordinate corresponds to the forward characteristic of the set of Esaki diodes ED_1 , and a left half of the curve c corresponds to the forward characteristic of the set of Esaki diodes ED_2 . Accordingly, all operations described with reference to FIGS. 1, 2 and 3 can be applied without modification to this embodiment shown in FIG. 5, and the input-output characteristic of this embodiment can be designated similarly by the curve d shown in FIG. 4. As previously described, values V_{T1} , V_{T2} , $-V_B$ and V_A can be varied in respective wide ranges in this embodiment. Moreover, since jumping operation caused at each of the values V_{T1} and V_{T2} of the input-output characteristic is very high due to the negative resistance of the Esaki diode, high frequency response can be obtained in this embodiment.

The embodiment shown in FIG. 5 is suitable to realize a fail-safe logical circuit. If a resistance equal to the resistance of the transistor TR_1 or TR_2 in a case of no input signal is inserted in series at the collector of the transistor TR_1 and TR_2 , the output voltage V_i is always zero in a case of short or open of the emitter-collector path of each of the transistors TR_1 and TR_2 . In another main fault where the sets of Esaki diodes ED_1 and ED_2 are short-circuited, the output voltage V becomes zero. To make the output voltage V_o zero at the open-circuit of the Esaki diodes ED_1 and ED_2 , two ternary logic circuits of this invention having a pair of common output terminals J_o and E may be used.

In the above description, it is assumed that the nonlinear characteristic of the load resistance is a double N-shaped voltage-current characteristic. However, the ternary logic circuit of this invention can be also constructed by the use of a load resistance having a double S-shaped voltage-current characteristic.

What we claim is:

1. A ternary logic circuit comprising:
a first controllable resistance whose resistance increases as the value of the input voltage thereof increases;
a second controllable resistance connected in series to the first controllable resistance, the resistance of the second controllable resistance decreasing as the value of the input voltage thereof increases;
a DC source operatively connected to the series-connection of the first and second controllable resistances to apply a plus voltage to one of the first and second controllable resistances and to apply a minus voltage to the other of the first and second controllable resistances;

means for applying a common input voltage to the first and second controllable resistances; and a load resistance connected across the ground and a junction between the first controllable resistance and the second controllable resistance, the load resistance having a nonlinear current-voltage characteristic in which the terminal voltage of the load resistance assumes a low value until the current of the load resistance exceeds a plus or minus threshold level after starting from zero and assumes one of plus and minus substantially constant possible values each higher than the low value when the current of the load resistance exceeds the plus and minus threshold levels respectively; whereby an output voltage developed across the load resistance is so controlled in accordance with the input voltage that the output voltage assumes substantially zero when the input voltage assumes a value included in a first voltage-range between a predetermined plus voltage and a predetermined minus voltage, that the output voltage assumes a substantially constant plus voltage when the

input voltage assumes a value included in one of a second voltage range and a third voltage range excluded from the first voltage-range to plus side and minus side respectively, and that the output voltage assumes a substantially constant minus voltage when the input voltage assumes a value included in the other of said second voltage-range and said third voltage-range.

2. A ternary logic circuit according to claim 1, in which the first controllable resistance and the second controllable resistance are respectively a PNP transistor and a NPN transistor, respective emitter-collector paths of the transistors being connected in series, the input voltage being applied to both bases of the transistors.

3. A ternary logic circuit according to claim 2, in which the load resistance comprises two sets of Esaki diodes connected in series to each other in opposite directions, each of the sets of Esaki diodes comprising a plurality of Esaki diodes connected in series to one another in the same direction.
